(57) **CLAIM**

The ornamental design for a vehicle pilar with authentication display screen, as shown and described.

DESCRIPTION

FIG. 1 is a front and left side perspective view of a first embodiment of a vehicle pilar with authentication display screen, showing our design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and

FIG. 8 is a front view thereof, shown in a condition of use;

FIG. 9 is a front and left side perspective view of a second embodiment of a vehicle pilar with authentication display screen, showing our design;

FIG. 10 is a front view thereof;

FIG. 11 is a rear view thereof;

FIG. 12 is a right side view thereof;

FIG. 13 is a left side view thereof;

FIG. 14 is a top view thereof;

FIG. 15 is a bottom view thereof; and

FIG. 16 is a front view thereof, shown in a condition of use.

FIG. 17 is a front and left side perspective view of a third embodiment of a vehicle pilar with authentication display screen, showing our design;

FIG. 18 is a front view thereof;

FIG. 19 is a rear view thereof;

FIG. 20 is a right side view thereof;

FIG. 21 is a left side view thereof;

FIG. 22 is a top view thereof;

FIG. 23 is a bottom view thereof; and,

FIG. 24 is a front view thereof, shown in a condition of use.

The dash-dash broken lines illustrate portions of the vehicle pilar with authentication display screen that form no part of the claimed design. The dash-dash broken lines in FIGS. 8, 16, and 24 depicting a vehicle illustrate environmental
